US00D471624S

(12) **United States Design Patent** (10) Patent No.: **US D471,624 S**
 Hurlstone et al. (45) Date of Patent: **** Mar. 11, 2003**

(54) **VENTILATION ROTOR**

(75) Inventors: **Christopher John Hurlstone**, Newport (GB); **Mark Anthony Di Cioccio**, Bury St. Edmunds (GB); **Reuben Wu**, Saffron Walden (GB); **Sophie Rebecca Butler**, Swavesey (GB); **Robert Cheetham Halstead**, Enfield (GB); **Alan Peter Tye**, Tring (GB); **Kevin Alan Alex Tye**, Tring (GB)

(73) Assignee: **Flettner Ventilator Limited**, London (GB)

(**) Term: **14 Years**

(21) Appl. No.: **29/148,496**

(22) Filed: **Sep. 20, 2001**

(30) **Foreign Application Priority Data**

Mar. 20, 2001 (GB) 2100462

(57) **CLAIM**

We claim the ornamental design for a ventilation rotor, as shown and described.

DESCRIPTION

FIG. 1 is a top perspective view thereof;
 FIG. 2 is a bottom perspective view thereof;
 FIG. 3 is a front view thereof, the rear view thereof corresponding to the front view;
 FIG. 4 is a first side view thereof, the second side view thereof corresponding to the first side view;
 FIG. 5 is a top plan view thereof; and,
 FIG. 6 is a bottom plan view thereof.
